[57] CLAIM

The ornamental design for a package for contact lens containers, as shown and described.

DESCRIPTION

FIG. 1 is a perspective view of a package for contact lens containers showing my new design;

FIG. 2 is a top plan view thereof;

FIG. 3 is a front elevation view thereof;

FIG. 4 is a right side elevational view thereof; the left side elevational view being a mirror image thereof;

FIG. 5 is a rear elevational view thereof;

FIG. 6 is a bottom plan view thereof;

FIG. 7 is a perspective view thereof; in open position with the perforations of the package broken;

FIG. 8 is a perspective view thereof; with the perforations of the package broken and the front tab tucked in; and,

FIG. 9 is a plan view of the package in an unassembled condition.

The broken lines showing of contact lens containers is for illustrative purposes only and forms no part of the claim.
